INDIVIDUAL SALT CONTAINER

Filed Feb. 29, 1928

UNITED STATES PATENT OFFICE

DAVID O. FORD, OF LYNCHBURG, VIRGINIA, ASSIGNOR TO SANITARY SHAKER CORPORATION, OF LYNCHBURG, VIRGINIA, A CORPORATION OF VIRGINIA

INDIVIDUAL SALT CONTAINER

Application filed February 29, 1928. Serial No. 257,984.

The invention provides an individual container for salt and like food seasoning that may be carried in the vest pocket for convenience and when empty thrown away since its cost is nominal.

The invention contemplates a container for the salt or other food seasoning usually dispensed by a shaker or holder provided with a perforated top, and a jacket for enclosing 10 the container and covering the perforated top to exclude dust and prevent wasting of the contents.

While the drawings illustrate a preferred embodiment of the invention, it is to be understood that in adapting the means to meet specific needs and requirements, the design may be varied and such other changes in the minor details of construction may be resorted to within the scope of the invention as claimed, 20 without departing from the spirit thereof.

For a full understanding of the invention and the merits thereof reference is to be had to the following description and the drawings hereto attached, in which:

25 Figure 1 is a perspective view of the container and jacket therefor, embodying the invention.

Figure 2 is a perspective view of the container on an enlarged scale, the jacket being 30 omitted.

Figure 3 is a sectional view on the line 3—3 of Figure 1.

Figure 4 is a sectional view of the jacket taken on a line just below the top and above 35 the plane of the sides.

Figure 5 is a plan view of the blank from which the container is formed.

Figure 6 is a similar view of the blank from which the jacket is formed.

40 Corresponding and like parts are referred to in the following description and designated in the several views of the drawings by like reference characters.

In the preferable construction, stout paper 45 is employed in the construction of the container and jacket. Any cheap material suitable for the purpose may be utilized. The container is formed of a blank having the outline indicated in Figure 5 of the drawing and the jacket is similarly formed from a blank sub-

stantially as shown in Figure 6 of the drawing. The blanks are folded along the dotted lines and when shaped are made secure by a suitable adhesive.

Referring to Figure 5 of the drawing, the 55 blank includes a front 1, sides 2 which taper similarly throughout their length, a sectional back comprising the elements 3, a bottom 4, top 5 flaps 6 and 7, and tabs 8 and 9. The top 5 is perforated as indicated at 10, to admit of 60 dispensing salt or analogous food seasoning by shaking in a manner well understood. The sides 2 are folded in the same direction to occupy a position perpendicular to the front 1 and the sections 3 are folded inwardly to occupy a position opposite and about parallel with the front 1 and with their marginal portions overlapping and made secure by a suitable adhesive. The bottom 4 is folded to close the lower end of the container and is made secure by folding the flap 7 against the back and 65 securing it by means of an adhesive. The tabs 9 are folded inwardly to overlap the end portions of the bottom 4. The tabs 8 are preferably formed at the ends of the top 5 and taper 70 slightly and are folded to lie against the sides 2 to which they are secured by means of an adhesive. The top 5 is folded to extend over and close the top of the container. The flap 6 is tucked within the container to lie against 75 the inner side of the back and is usually retained in place by friction. The container is diminutive and adapted to hold a small portion of salt or other food seasoning so as to possesss a limited use and to be thrown away 80 after service.

The blank comprising the jacket includes a front 11, a top 12, a closing flap 13, sides 14, back 15, and sealing flap 16. The blank is folded to bring the sides 14 perpendicular to 90 the front 11 and the back 15 opposite said front and inclined thereto. The sides 14 taper. The sealing flap 16 is folded against the inner side of a marginal edge portion of the front 11 and is adhesively secured thereto. 95 The closing flap 13 is adapted to engage the inner side of the back 15 and is adapted to occupy a position between the container and part 15 when the container is placed within the jacket, as indicated most clearly in Figures 1 100

and 3 of the drawings. The dimensions of the jacket are such as to admit of a snug fit between the container and the jacket when the parts are assembled. The wedge form of the 5 container and jacket insures a binding action when pressing the container within the jacket.

Having thus described the invention, what I claim is:

1. An individual container for salt and 10 analogous food seasoning comprising a wedge-shaped body having a perforated top, and a wedge-shaped jacket adapted to snugly receive the container and including a top to extend over and close the perforations in the 15 top of the container and having a flap to be tucked between adjacent sides of the container and the jacket and retained in place by a wedging action.

2. An individual container for salt and like 20 articles of food seasoning, the same consisting of a wedge shaped body having a perforated top, and a jacket of wedge form adapted to snugly receive the container and formed from a blank including a front, a back, tapering sides, a closure flap, a top for extending over and closing the perforations in the 25 top of the container, and a closing flap adapted to be tucked into the jacket to occupy a position between adjacent sides of the container 30 and jacket.

In testimony whereof I affix my signature.

DAVID O. FORD. [L. s.]
